UNITED STATES PATENT OFFICE.

THOMAS SYKES, OF MARTINS FERRY, OHIO.

ORCHARD-HEATER.

1,082,101.

Specification of Letters Patent. Patented Dec. 23, 1913.

Application filed April 4, 1913. Serial No. 752,776.

To all whom it may concern:

Be it known that I, THOMAS SYKES, a citizen of the United States of America, and resident of Martins Ferry, county of Belmont, and State of Ohio, have invented certain new and useful Improvements in Orchard-Heaters, of which the following is a specification.

This invention relates to orchard heaters, and more particularly to that type of heaters in which oil is used as fuel.

The primary object of the invention is to provide an orchard heater which is adapted to generate a maximum amount of heat with a minimum consumption of fuel, and which is provided with means whereby combustion may be accelerated and retarded for regulating the degree of heat generated thereby.

A further object is to provide an orchard heater in which the oil receptacle may be of relatively large capacity and in which combustion upon the surface of the oil is confined to a comparatively small portion of the area of said surface. And a still further object is to provide a device of the character mentioned in which a large proportion of the oil is artificially gasified and delivered to a combustion point or chamber located without the oil receptacle for producing an intense heat.

With these and other objects in view, the invention resides in the features of construction, arrangement of parts and combinations of elements which will hereinafter be exemplified, reference being had to the accompanying drawings, forming a part of this specification, in which—

Figure 1 is a view of the invention partly in side elevation and partly in broken section; Fig. 2 is a view of the same partially in top plan and partially in broken section; Fig. 3 is a longitudinal section of the same on the line 3—3, Fig. 2; and Fig. 4 is an end elevation of the invention.

Referring to said drawings, in which like designating characters distinguish like parts throughout the several views, 1 indicates an oil receptacle which may be of any suitable form, but which is preferably rectangular, as shown. Fitted closely within the top of said receptacle is a flat removable lid or cover 2. Carried by said cover 2 adjacent to one end of the latter and opening therethrough is the upper end of a tube 3, of frusto-conical form, the lower end of which is adapted to seat upon the bottom of the

receptacle 1 when said cover occupies a seated position. Said tube constitutes a fire-pot within which the oil is ignited and burns without admitting the flame to the oil in the receptacle proper—that is, to that portion 4 of the receptacle which may be termed the reservoir. The oil feeds to the fire-pot in a suitable manner, as through one or more small openings 5 formed by notching the lower end of the tube 3.

Mounted over the top of the receptacle 1 is a second cover 6 which is of substantially bow shape in cross section, and which is preferably corrugated, as shown, for the purpose of increasing its rigidity. A stack 7 is mounted over an opening provided in said cover 6 at the end opposite that which overlies the fire-pot, and extending upward to and concentric with said opening is a tubular gas-conduit 8 which leads through the cover 2. The upper end of said conduit is of less diameter than that of the opening in the cover 6 and is adapted to conduct into said stack gases which are generated in the reservoir 4, there to meet the flame from the burning oil in the fire-pot as said flame issues through the annular passage between the mouth of said conduit and the periphery of the said opening in the cover 6.

Rigidly mounted upon the top of the cover 6 in encircling concentric relation, to the stack 7 at a suitable distance from the latter is a ring or collar 10 about which is removably fitted a plain cylindrical apron or shield 11 which is designed to shield the stack from gusts of wind which would have a tendency to render combustion within the stack more or less fitful or unsteady. Said ring or collar 10 is deeply corrugated, as shown, so that numerous small passages 12 are afforded for admitting a steady draft of air at the lower end of the shield, which latter has its lower end scalloped, as shown at 9, to admit such draft of air. Perforations 13 are preferably provided in the stack for admitting air for mixing with the gas for facilitating combustion within said stack. For directing a volume of air into said stack together with the gas from the reservoir, a pipe 14 is directed horizontally through the front end of the cover 6 and into the conduit 8, as shown. A hinged lid-like damper 15 is provided at the rear end of the cover 6 whereby the admission of air to the fire-pot is controlled and whereby the draft for carrying the flame forward from

85

110

the fire-pot to the interior of the stack is regulated. An upright arm 16, formed by turning at a right angle the end of the wire constituting the pintle of the hinge, has one end of a forwardly extending rod 17 pivotally connected thereto; and a hook or bill 18 formed at the front end of said rod is adapted to be directed into one of a plurality of spaced holes 19, provided in an outwardly directed flange 20 carried by the cover 6, for maintaining the damper in adjusted position.

For preventing the flame resulting from combustion of the gas within the stack from dropping back to the surface of the oil within the reservoir 4, a circular netting or screen 21 of wire is preferably employed, the same being removably seated upon the top of the conduit 8. Said screen has one or more openings, as 28, provided therein adjacent to its periphery to permit of the passage therethrough of flame from the fire-pot 3.

Mounted at a suitable point in the cover 2 over the reservoir 4 is an upwardly tapered filling tube 23 which projects outward through an opening 24 provided in the cover 6. By removal of a covering or cap 25 provided for said tube, the reservoir may be readily filled, or the fuel replenished without disturbing any of the heater parts and without the necessity of extinguishing the fire. The lateral edges of the cover 6 are downwardly inclined and terminate in hooks 26 which are adapted to be sprung into clasping engagement with the lateral edges or beads 27 of the receptacle 1, as shown in Fig. 4.

In practice, the oil within the fire-pot is ignited, and the flame and heat resulting from the combustion are directed forward between the covers 2 and 6 and into the stack 7, as indicated by arrows in Fig. 3, passing through the annular passage surrounding the conduit 8 and through the opening 28 in the screen 21. In passing through the restricted passage between the covers 2 and 6 much heat is absorbed by the cover 2 and is thereby communicated to the oil in the reservoir 4, resulting in a rapid vaporization of said oil. The vapor or gas thus generated in the reservoir is conducted upward through the conduit 8 and netting 21 to the stack, wherein it meets the flame from the fire-pot and is consumed, producing a heat of great intensity. As the gas passes through said conduit it becomes mixed with air admitted through the pipe 14. By adjustment of the damper 15 the combustion and amount of heat generated may be readily controlled, the rapidity of combustion being dependent upon the volume of air admitted past said damper. To extinguish the fire in the fire-pot, said damper is completely closed.

It will be noted that the cover 2 with attached fire-pot, gas-conduit and filling tube is adapted for nesting with similar parts, and that each of the remaining parts are readily removable and are likewise adapted for packing in nested relation, provision being thus made whereby space may be greatly economized when a number of the heaters are prepared for shipment.

Having thus described my invention, what I claim as new, and desire to secure by Letters Patent, is—

1. An orchard heater comprising an oil receptacle, a fire-pot having an opening at its lower end mounted within said receptacle, a cover mounted upon said receptacle to prevent communication of flame from the fire-pot to the portion of said receptacle outside the fire-pot, a second cover overlying the receptacle to afford a passageway from the fire-pot over the first cover for the products of combustion, said second cover having an opening therein, a stack mounted about said opening, a gas conduit leading into said stack from the interior of the receptacle, and means supplying air to the conduit.

2. An orchard heater comprising an oil receptacle, a fire-pot having an open lower end mounted within said receptacle, a cover mounted upon said receptacle whereby communication of flame from the fire-pot to the portion of said receptacle outside the fire-pot is prevented, a second cover overlying the receptacle to afford a passageway from the fire-pot over the first cover for the products of combustion, said second cover having an opening therein, a stack mounted on the second cover about said opening, a gas conduit leading into said stack from the interior of the receptacle, means for supplying air to the conduit, and controllable means for admitting a draft through said passageway.

3. An orchard heater comprising an oil receptacle, a fire-pot mounted within said receptacle and having communication through its lower end with the latter, a cover mounted upon said receptacle whereby communication of flame from the fire-pot to the portion of said receptacle outside the fire-pot is prevented; a second cover overlying the receptacle to afford a passageway from the fire-pot over the first cover for the products of combustion, said second cover having an opening therein, a stack mounted on the second cover about said opening, a gas conduit leading into said stack from the interior of the receptacle, means supplying air to the conduit, and means whereby combustion of oil within the fire-pot may be regulated.

4. An orchard heater comprising an oil receptacle, a fire-pot mounted within said receptacle and having communication

- through its lower end with the latter, a cover mounted upon said receptacle whereby communication of flame from the fire-pot to the portion of said receptacle outside the fire-pot is prevented, means whereby the products of combustion from said fire-pot are caused to pass over said cover and impart heat to the oil in the receptacle, a conduit for gas leading from the interior of said receptacle, 5 a stack encircling the mouth of said conduit and adapted to receive the products of combustion from the fire-pot, and means supplying air to the conduit for facilitating combustion of gas within the stack.
- 10 5. An orchard heater comprising an oil receptacle, an open fire-pot seated within said receptacle and having communication through its lower end with the latter, means covering the portion of said receptacle not occupied by said pot, a conduit leading upward from the interior of said receptacle through said covering means, a cover overlying said receptacle above said fire-pot and said covering means whereby a passage for 20 the products of combustion from the fire-pot is constituted, said cover having an opening therethrough, a stack with which both said passage and said conduit communicate through said opening, and means supplying air for mixing with gas generated within the receptacle.
- 25 6. An orchard heater comprising an oil receptacle, an open fire-pot seated within said receptacle and having communication through its lower end with the latter, means covering the portion of said receptacle not occupied by said pot, a conduit leading upward from the interior of said receptacle through said covering means, a cover overlying said receptacle above said fire-pot and said covering means whereby a passage for 30 the products of combustion from the fire-pot is constituted, said cover having an opening therethrough, a stack with which both said passage and said conduit communicate through said opening, and means supplying air for mixing with gas generated within the receptacle.
- 35 7. An orchard heater comprising an oil receptacle, an open fire-pot seated within said receptacle and having communication through its lower end with the latter, means covering the portion of said receptacle not occupied by said pot, a conduit leading upward from the interior of said receptacle through said covering means, a cover overlying said receptacle above said fire-pot and said covering means whereby a passage for 40 the products of combustion from the fire-pot is constituted, said cover having an opening therethrough, a stack with which both said passage and said conduit communicate through said opening, and means supplying air for mixing with gas generated within the receptacle, and draft regulating means whereby combustion of oil is controlled.
- 45 8. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 50 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, and draft-regulating means associated with said cover whereby combustion in the pot is controlled.
- 55 9. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 60 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, draft-regulating means associated with said cover whereby combustion in the pot is controlled, and a shield located in encircling relation to the stack.
- 65 10. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 70 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, draft-regulating means associated with said cover whereby combustion in the pot is controlled.
- 75 11. An orchard heater comprising an oil receptacle, a fire-pot seated within said receptacle, means for maintaining the oil in the fire-pot and in said receptacle at a uni- 80
- 85 12. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 90 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, draft-regulating means associated with said cover whereby combustion in the pot is controlled.
- 95 13. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 100 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, draft-regulating means associated with said cover whereby combustion in the pot is controlled, and a shield located in encircling relation to the stack.
- 105 14. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 110 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, draft-regulating means associated with said cover whereby combustion in the pot is controlled.
- 115 15. An orchard heater comprising an oil receptacle divided to form a fire-pot and a reservoir, means supplying oil from said reservoir to said pot, means excluding from the reservoir flame resulting from combustion in the pot, a conduit for gas leading from the reservoir through said flame-excluding means, a cover having an opening 120 therein surmounting the reservoir and the pot and affording a passage over the reservoir for the products of combustion in the pot, a stack mounted on said cover about said opening, both said passage and said conduit having communication with said stack through said opening, means supplying air for mixing with the gas, draft-regulating means associated with said cover whereby combustion in the pot is controlled, and means whereby the reservoir may be filled 125 without removal of said cover.
- 125 16. An orchard heater comprising an oil receptacle, a fire-pot seated within said receptacle, means for maintaining the oil in the fire-pot and in said receptacle at a uni- 130

form level, a cover for that portion of the receptacle not occupied by the fire-pot, means mounted over said receptacle whereby the products of combustion from the fire-pot are directed along a path in contact with said cover, said means having an opening therein, a stack located over said directing means and having communication through said opening with said path, a conduit leading through said cover for directing gas from the receptacle into said stack, means preventing flame from passing downward through said conduit, and means supplying air to the conduit.

12. An orchard heater comprising an oil receptacle, a fire-pot seated within said receptacle, means for maintaining the oil in the fire-pot and in said receptacle at a uniform level, a cover for that portion of the receptacle not occupied by the fire-pot, means mounted over said receptacle whereby the products of combustion from the fire-pot are directed along a path in contact with said cover, said means having an opening therein, a stack located over said directing means and having communication through said opening with said path, a conduit leading through said cover for directing gas from the receptacle into said stack, means preventing flame from passing downward through said conduit, means supplying air to the conduit for facilitating combustion in the stack, means for supplying air to the fire-pot, and an adjustable damper controlling the last mentioned means.

13. An orchard heater comprising an oil receptacle, a fire-pot seated within said receptacle, means for maintaining the oil in the fire-pot and in said receptacle at a uniform level, a cover for that portion of the receptacle not occupied by the fire-pot, a second cover disposed over and at a distance

from the first cover whereby is formed a passage for the products of combustion from said fire-pot, said second cover having an opening therein, said passage leading along the top of said first cover, a stack disposed upon the second cover about said opening, said passage having communication with said stack through said opening, a conduit leading from the interior of the receptacle for conducting gas into said stack, a pipe for conducting air into said conduit, and means associated with the second cover for controlling the rate of combustion in the fire-pot.

14. An orchard heater comprising an oil receptacle, a fire-pot seated within said receptacle, means for maintaining the oil in the fire-pot and in said receptacle at a uniform level, a cover for that portion of the receptacle not occupied by the fire-pot, a second cover disposed over and at a distance from the first cover whereby is formed a passage for the products of combustion from said fire-pot, said second cover having an opening therein, said passage leading along the top of said first cover, a stack disposed upon the second cover about said opening, said passage having communication with said stack through said opening, a conduit leading from the interior of the receptacle for conducting gas into said stack, a pipe for conducting air into said conduit, a wire netting disposed across the mouth of said conduit, and means for controlling the rate of combustion in the fire-pot.

In testimony whereof, I affix my signature in presence of two subscribing witnesses.
